WALL AND CEILING COVERING.

No.19,615.

Patented Jan. 28, 1890.

UNITED STATES PATENT OFFICE.

PAUL GROEBER, OF RUTHERFORD PARK, NEW JERSEY, ASSIGNOR TO
FREDERICK BECK, OF NEW YORK, N. Y.

DESIGN FOR A WALL AND CEILING COVERING.

SPECIFICATION forming part of Design No. 19,615, dated January 28, 1890.

Application filed December 26, 1889. Serial No. 335,046. Term of patent 3½ years.

To all whom it may concern:

Be it known that I, PAUL GROEBER, a citizen of the United States, residing at Rutherford Park, in the county of Bergen and State of New Jersey, have invented and produced a new and original Design for a Wall and Ceiling Covering, of which the following is a specification, reference being had to the accompanying drawing, forming part thereof.

10 The leading feature of my design consists of a central four-leaf ornament 1, having a central button and a small button at the four angles, each on a stalk.

The field of the design is filled in with in-

terlacing and entwining ribbon ornaments 15 2, ornamented with buttons 3 and groups of leaves 4, the whole forming a geometrical design.

What I claim is—

The design for a wall and ceiling covering 20 herein shown and described, consisting of a geometrical design consisting of leaf ornaments, buttons, and entwining ribbon forms.

PAUL GROEBER.
